UNITED STATES PATENT OFFICE.

JACOB T. JOHNSON, OF ATLANTA, GEORGIA.

COMBINATION FAUCET.

Application filed December 20, 1922. Serial No. 608,044.

To all whom it may concern:

Be it known that I, JACOB T. JOHNSON, a citizen of United States, residing at Atlanta, in the county of Fulton and State of

5 Georgia, have invented certain new and useful Improvements in Combination Faucets, of which the following is a specification, reference being had therein to the accompanying drawings.

10 The present invention relates generally to valves and faucets, more particularly combination hot and cold water faucets, such as are used for discharging hot or cold water or a mixture thereof for bath tubs, kitchen

15 sinks, wash stands, barber shops, wall showers, and the like, and the invention forming the subject matter of the present application is an improvement in or another species in addition to the combination faucets disclosed in my Patent No. 1,336,236

20 granted April 6, 1920, and in my copending applications Serial Nos. 504,584 and 526,942 filed Oct. 1, 1921, and January 4, 1922, respectively.

25 In addition to the general object in providing a practical and efficient valve or faucet of that kind requiring the operation of only a single operating handle or member, as in the patent and applications supra,

30 it is the object of the invention to provide a novel and improved valve member for controlling the flow of hot and cold water and the discharge thereof, and for the further purpose of directing the hot and cold water 35 to a mixing chamber in such a way that there is no liability for either stream of water being backed up, such as when one stream is delivered at a higher pressure to the faucet or valve than the other stream.

40 Another object is the provision of such a valve or faucet in which the two liquids do not comingle until they move in the same direction toward the discharge outlet, to avoid back pressure on either stream of 45 liquid, the two streams being prevented from having a "head-on" collision in the faucet, to avoid jars and vibrations, as well as eliminating back pressure on either stream.

50 A further object is the provision in such a faucet or valve of novel means for breaking up or dividing the streams of liquid, so as to avoid the whirling or agitated dis-

charge of the water or liquid from the faucet, for the purpose of providing a smooth discharging stream which will not splash 65 objectionably.

With the foregoing and other objects in view, which will be apparent as the description proceeds, the invention resides in the construction and arrangement of parts, as 60 hereinafter described and claimed, it being understood that changes can be made within the scope of what is claimed, without departing from the spirit of the invention.

The invention is illustrated in the accompanying drawings, wherein—

Figure 1 is a vertical section of the valve in open position, portions being shown in elevation.

Fig. 2 is a vertical section of the valve 70 member taken on the line 2—2 of Fig. 1, at right angles to the line of view in Fig. 1, the stem being shown in elevation.

Figs. 3 and 4 are horizontal sections on the respective lines 3—3 and 4—4 of Fig. 1. 75

Fig. 5 is a view somewhat similar to Fig. 1, showing a modified construction, with the valve member partly in elevation and partly in section.

Figs. 6, 7 and 8 are elevations of valve 80 members having different forms of ports therein.

Fig. 9 is a cross-section on the line 9—9 of Fig. 8.

Fig. 10 is a cross-section of another modified form of valve member having the channels open at the periphery or opposite sides of the valve member.

Fig. 11 is a cross section of another valve member showing a further modification. 90

Referring to Figs. 1, 2, 3 and 4, the body or casing 14 is of suitable metal and has a vertical chamber 15 and hot and cold water inlet passages 16 and 17, respectively, leading to the opposite sides of a smooth cylindrical wall of the chamber 15, said casing having suitable means for the connection of hot and cold water supply pipes. The lower end of the casing terminates in a discharge nipple or nozzle 18, and the lower end of the chamber 15 is gradually reduced in diameter or tapered, as at 19, so that the wall of the chamber converges and merges into the nozzle or outlet portion 18 to provide a 95 100

ed, as at 20, at a point above the passages 16 and 17, and the upper end of the chamber 15 is closed by a cap 21 threaded onto the upper end of the casing.

The valve member 22 is externally screw-threaded as at 23, near its upper end to engage the screw-threads 20, for the longitudinal or axial movement of the valve member within the chamber 15 when the valve member is rotated, it being noted that the screw-threads between the valve member and casing are located at that side of the passages 16 and 17 opposite to the outlet of the casing. The valve member has a smooth cylindrical surface fitting the smooth cylindrical wall of the chamber 15 below the screw threads.

The valve stem or rod 24 extends longitudinally through the valve member at the axis thereof, for turning the valve member, and the upper terminal of said stem projects through the cap 21 and has a suitable handle 25 for conveniently turning the valve member. A rubber or other suitable gasket or packing 26 is disposed around the stem 24 to bear and fit against the cap 21 on the interior thereof, so as to prevent leakage of the water past the cap. Said gasket or packing is retained in place by a metal disk or washer 27 seated on the upper end of the casing, although any necessary or suitable packing can be used.

In order to control the flow of hot and cold water, the valve member 22 is provided at opposite sides of its axis with the longitudinal channels or passages 28 and 29 extending to the lower end of the valve member, and the upper ends of said channels or passages open at the opposite sides of the valve member between the ends of the smooth cylindrical surface of said member, to provide the respective hot and cold water ports 30 and 31 to register with the hot and cold water passages 16 and 17. The ports 30 and 31 are so arranged that either of them may fully register with the corresponding inlet passage, or the two ports may partially register with both inlet passages when a mixture of hot and cold water is wanted. The control of hot and cold water is obtained by turning the valve member.

The discharge of water from the valve is prevented when the valve member is screwed down, and, for this purpose, the lower end of the valve member has a depending finger or reduced portion 32, through which the valve stem or rod 24 extends. The finger or said 32 is arranged centrally of the valve member and casing, and the stem 24 has a collar or enlargement 33 seating against or abutting the end of the finger 32, and said stem also has a collar 34 bearing against the upper end of the valve member, to secure

tip of washer 27 is secured to the collar 33 of the terminal portion 33 of the stem 24, to be moved with the valve member, and may be of rubber, fibre or other material to have a compression fit on the valve seat surrounding the outlet, so that when the valve member is screwed downwardly, the valve tip 35 will seat over the discharge port or outlet with a compression fit to tightly close said outlet, thereby providing a "compression valve structure." The discharge of any water from the casing is therefore shut off when the valve member is screwed down, and, furthermore, when the valve member is in this position, the ports 30 and 31 are out of registration with the passages 16 and 17, so that the valve member extends across and closes the passages 16 and 17, while the wall of the casing extends across and closes the ports 30 and 31. The inlet passages and outlet of the casing and passages of the valve member are therefore all closed when the valve member is in closed position, to prevent leakage and to also relieve the packing of pressure.

When the valve member is screwed upwardly, the discharge port or outlet is opened, and the ports 30 and 31 of the valve member can then be brought into and out of registration with the inlet passages for the discharge of hot or cold water, or a desired mixture thereof when water of an intermediate temperature is wanted. The passages or channels 28 and 29 of the valve member will direct the hot and cold water from the inlet passages longitudinally in the valve member to discharge at opposite sides of the finger 32 into the mixing chamber between the discharge end of the casing and lower end of the valve member. The hot and cold water are therefore directed toward the outlet before comingling, and this eliminates the possibility of either stream being backed up or subject to back pressure, such as when one stream is delivered to the valve at greater pressure than the other stream. The valve member also prevents the streams from mixing in the valve member until they are discharged from the valve member. The inflowing streams cannot, therefore, have a head-on collision in the valve, such as would produce a jarring or vibration of the plumbing, or the back pressure on either stream.

Means is provided for reducing or eliminating the splashing or spraying of the water in discharging from the valve. Thus, the lower end of the valve member is formed with an annular recess 36 surrounding the finger or stud 32, and forming an annular skirt 37 at the end of the valve member fitting the wall of the casing and spaced from the finger 32, with the passages or channels 28 opening into the recess 36.

the skirt 37 and the finger 32, said ring fitting around the finger within the recessed 5 end of the valve member, and said ring has the annular series of apertures 39, so that the ring provides a strainer for the discharge end of the valve member. Thus, the water flowing from either or both 10 passageways or channels of the valve member will pass into the recess 36, and the streams will be broken or divided up by the apertures 39, so that the water will flow from the valve member in jets into the mixing chamber. 15 This will prevent the sudden rush of the water into the mixing chamber, and the whirling motion of the water in said chamber or through the outlet, and, as a result, the water has a smooth mixing action, for 20 the smooth discharge of the water from the valve, without spraying or splashing objectionably. As shown, the ring or strainer 38 is a piece separate from the valve member having a friction fit with the skirt 37 25 and finger 32, in order that said ring can be removed for cleaning or replacement.

Fig. 5 illustrates a modification, in that the screw threads of the valve member 22^a are formed on a sleeve or collar 23^a removably fitted on the upper end portion of the valve member, and that the screw threads of the casing are formed in a bushing 20^a removably fitted in the upper end portion 30 of the casing 14^a, whereby said threaded 35 portions of the valve member and casing can be replaced when worn out or damaged. In this construction, the valve stem 24^a is also shown as being integral with the upper end of the valve member.

Figs. 6, 7 and 8 show the ports 30^b, 31^b and 31^c of the respective valve members of different shapes, each port having a large end for full registration with the corresponding inlet passage and a tail of narrower width for restricting the flow as the larger or wider end is moved away from the inlet passage.

Fig. 9 shows the valve member 22^c with the opposite ports 30^c and 31^c of the shape shown in Fig. 8, and the passages or channels 28^c and 29^c of the valve member are also of greater width than shown in Fig. 3, said passages being of widths equal to the lengths of the ports, whereby to provide for 55 a greater turning movement of the valve member in controlling the flow of hot and cold water, which may be especially desirable for showers.

Fig. 10 shows the passages or channels 28^d and 29^d open at the opposite sides of the valve member, whereby the water will flow along the wall of the casing in passing through said passages.

Fig. 11 suggests the use of webs 40 between the skirt 37^e and finger 32^e of the

water in the recess 36.

Having thus described the invention, what is claimed as new is:—

1. A valve comprising a valve casing having inlets and an outlet, a valve member within the casing having ports to register with said inlets, there being a mixing chamber between the outlet and valve member, 75 the valve member having separate passages leading from said ports and having a recess to which both of said passages extend, and a strainer member disposed between said recess and chamber.

2. A valve comprising a valve casing having inlets and an outlet, a valve member within the casing having ports to register with said inlets, there being a mixing chamber between the outlet and valve member, 85 the valve member having separate passages leading from said ports and having a recess to which both of said passages extend, and a strainer member carried by the valve member and disposed across said recess.

3. A valve comprising a casing having a smooth cylindrical wall, inlets leading to said wall at opposite sides, and an outlet at one end of the casing, a valve member having a smooth cylindrical surface fitting said 95 wall of the casing, said valve member having a screw-threaded connection with the casing, the valve member having ports at opposite sides to register with said inlets and having a recess in that end adjacent to the outlet, the casing having a mixing chamber between said recess and outlet, the valve member having separate passages leading from said ports to said recess, and a strainer member carried by the valve member and disposed across said recess.

4. A valve comprising a casing having a smooth cylindrical wall, inlets leading to said wall at opposite sides, and an outlet at one end of the casing, a valve member having a smooth cylindrical surface fitting said wall of the casing, the valve member having a screw-threaded connection with the casing, the valve member having a reduced portion at that end adjacent to the outlet, 110 said reduced portion having a valve portion to seat across said outlet, the valve member having an annular recess in said end surrounding said reduced portion and having ports to register with said inlets and communicating with said recess, said recess forming an annular skirt surrounding the recess, and an annular apertured strainer ring fitted between said reduced portion and skirt across said recess.

5. A valve comprising a casing having inlets and an outlet, a valve member in the casing having a reduced portion with a valve portion to close the outlet, the valve member having an annular recess surround-

ing to said recess and adapted to communicate with said inlets, and a strainer member carried by the valve member and disposed across said recess.

6. A valve comprising a casing having inlets and an outlet, a valve member in the casing having a reduced portion at one end with a valve portion thereon to seat across 10 said outlet, the valve member having an an-

15 member having passages leading to said recess and adapted to communicate with said inlets, and a strainer ring fitted between said skirt and reduced portion in said recess and having apertures.

In testimony whereof I hereunto affix my signature.

JACOB T. JOHNSON.
